US0D1009822S

(12) **United States Design Patent** (10) **Patent No.:** **US D1,009,822 S**
(45) **Date of Patent:** ** **Jan. 2, 2024**

(54) **MOBILE PHONE**

(71) Applicant: **BEIJING XIAOMI MOBILE SOFTWARE CO., LTD.**, Beijing (CN)

(72) Inventors: **Huacan Cui**, Beijing (CN); **Hongyu Chen**, Beijing (CN); **Xu Wei**, Beijing (CN)

(73) Assignee: **Beijing Xiaomi Mobile Software Co., Ltd.**, Beijing (CN)

(**) Term: **15 Years**

(21) Appl. No.: **35/514,180**

(22) Filed: **Mar. 3, 2022**

(80) **Hague Agreement Data**

Int. Filing Date: **Mar. 3, 2022**

Int. Reg. No.: **DM/220367**

Int. Reg. Date: **Mar. 3, 2022**

Int. Reg. Pub. Date: **May 6, 2022**

(30) **Foreign Application Priority Data**

Sep. 3, 2021 (CN) 202130582362.7

(51) **LOC (14) Cl.** **14-03**

(57) **CLAIM**

The ornamental design for a mobile phone, as shown and described.

DESCRIPTION

FIG. 1.1 is a front view of a first embodiment of a mobile phone showing our new design;

FIG. 1.2 is a back view of the mobile phone of FIG. 1.1;

FIG. 1.3 is a left view of the mobile phone of FIG. 1.1;

FIG. 1.4 is a right view of the mobile phone of FIG. 1.1;

FIG. 1.5 is a top view of the mobile phone of FIG. 1.1;

FIG. 1.6 is a bottom view of the mobile phone of FIG. 1.1;

FIG. 1.7 is a back perspective view of the mobile phone of FIG. 1.1;

FIG. 1.8 is a front perspective view of the mobile phone FIG. 1.1;

FIG. 2.1 is a front view of a second embodiment of a mobile phone showing our new design;

FIG. 2.2 is a back view of the mobile phone of FIG. 2.1;

FIG. 2.3 is a left view of the mobile phone of FIG. 2.1;

FIG. 2.4 is a right view of the mobile phone of FIG. 2.1;

FIG. 2.5 is a top view of the mobile phone of FIG. 2.1;

FIG. 2.6 is a bottom view of the mobile phone of FIG. 2.1;

FIG. 2.7 is a back perspective view of the mobile phone of FIG. 2.1;

(Continued)

FIG. 2.8 is a front perspective view of the mobile phone of FIG. 2.1;
 FIG. 3.1 is a front view of a third embodiment of a mobile phone showing our new design;
 FIG. 3.2 is a back view of the mobile phone of FIG. 3.1;
 FIG. 3.3 is a left view of the mobile phone of FIG. 3.1;
 FIG. 3.4 is a right view of the mobile phone of FIG. 3.1;
 FIG. 3.5 is a top view of the mobile phone of FIG. 3.1;
 FIG. 3.6 is a bottom view of the mobile phone of FIG. 3.1;
 FIG. 3.7 is a back perspective view of the mobile phone of FIG. 3.1; and
 FIG. 3.8 is a front perspective view of the mobile phone of FIG. 3.1.
